DESIGN FOR A BLOUSE OR SIMILAR
ARTICLE

Sam Platt, Brooklyn, N. Y.

Substituted for abandoned application Serial No.
130,701, June 14, 1946. This application December 20, 1947, Serial No. 143,268

Term of patent 3½ years

(CL. D3—25)

To all whom it may concern:

Be it known that I, Sam Platt, a citizen of the United States, residing at Brooklyn, New York, in the county of Kings and State of New York, have invented a new, original, and ornamental Design for a Blouse or Similar Article, of which the following is a specification, reference being had to the accompanying drawing, forming a part thereof.

In the drawing:

Fig. 1 is a front elevational view of a blouse or similar article, showing my new design; and

Fig. 2 is a rear elevational view of the same.

This is a substitute application for applicant's patent application, Serial #D. 130,701, filed June 14, 1946, which is now abandoned.

I claim:

The ornamental design for a blouse or similar article, as shown.

SAM PLATT.
